UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

DUMPING-CAGE FOR CRUSHERS AND PULVERIZERS.

No. 843,729.

Specification of Letters Patent.

Patented Feb. 12, 1907.

Application filed July 24, 1905. Serial No. 271,016.

To all whom it may concern:

Be it known that I, MILTON F. WILLIAMS, a citizen of the United States, residing at St. Louis, Missouri, have invented a certain new and useful Improvement in Dumping-Cages for Crushers and Pulverizers, of which the following is a full, clear, and exact description, such as will enable others skilled in the art to which it appertains to make and use the same, reference being had to the accompanying drawings, forming part of this specification, in which—

Figure 1 is a sectional view through my improved machine. Fig. 2 is a detail view of the dumping-cage. Fig. 3 is a sectional view on the line 3 3 of Fig. 1, and Fig. 4 is a perspective view showing one of the adjusting-wedges in operative engagement with the laterally-extending projection on the grinding-surface frame.

This invention relates to a new and useful improvement in dumping-cages for crushers and pulverizers, the object being to construct a cage in such manner that when the machine chokes it is possible to dump the contents thereof without raising the cover and removing the material from the top.

In the operation of my machine, especially where electric motors are employed as a driving medium, it sometimes happens that the fuse will blow out or other accidents happen during the time that the machine is in operation, causing the machine to stop and leaving the material being operated upon in the machine. Under these circumstances it is impossible to start the machine without first removing such material, it being necessary to get the machine up to full speed before introducing the material thereinto to be reduced.

My present invention therefore consists in making the grinding-surface or cage with which the revolving beaters coöperate to reduce the material wholly or partly movable, means for moving the same extending to the exterior of the machine, whereby in the event that the machine stops with a load or becomes choked it is possible for the operator to dump the contents of the cage and free the machine.

In the drawings, 1 indicates the side frames, and 2 the removable cover.

3 is the adjustable breaker-plate, arranged at the feed end of the machine and on which the material entering the machine is first

struck by the revolving beaters or hammers 4, mounted in suitable supports, in this instance 55 said supports being shown as crossed arms 5, having holes in their ends, whereby the hammers may be adjustably mounted therein.

6 indicates a portion of the cage or grinding-surface, preferably that located at the back 60 of the machine, which portion may be stationarily mounted in the side frames.

7 indicates a movable portion of the cage, the same being mounted in the side frames 8, pivotally arranged on a transversely-disposed 65 rod 9. These side frames 8 are connected in any suitable manner and preferably carry a cross-bar 10 at their free ends, in which are mounted screw-eyes 11. Chains 12 are secured to these screw-eyes and pass over a 70 winding drum or shaft 13, mounted in the side frames of the machine and preferably in the rear end thereof. On this winding-shaft is a ratchet-wheel 14, with which coöperates 75 a pawl 15. A hand-wheel 16 is also secured to the shaft, whereby the same may be rotated.

The operative position of the parts is shown in dotted lines in Fig. 1, and in the event that the machine chokes the pawl 15 is raised and the dumping portion 7 of the cage permitted 80 to drop, as shown by full lines in said Fig. 1. In this position the major portion of the contents of the machine is discharged through the bottom thereof, and after said discharge the winding-drum may be manipulated 85 through its hand-wheel to raise the cage to its normal operating position. If desired, the side frames 8 may be provided with threaded openings 17, which are designed to register with slots 18 in the side frames 1 when the 90 cage is in its normal operating position. Screws 19 may be inserted through the slots 18 into the opening 17 from the outside and wedge-blocks 20 introduced under the outer ends of said screws, so as to raise the movable section 7 to its proper position relative 95 to the striking-points of the hammers 4. These wedge-blocks are useful also in adjusting the movable section 7 to take up the wear of the hammers.

I have not herein specifically described the construction of the revolving beaters, as they form the subject-matter of a separate application filed by me on May 15, 1905, Serial No. 260,499. It should be understood, however, that my improved cage is not limited to

use in combination with the kind of beaters herein shown.

Having thus described the invention, what is claimed as new, and desired to be secured 5 by Letters Patent, is—

1. In a machine of the character described the combination of a casing, a shaft arranged horizontally in the casing and carrying pivotally-mounted hammers, a frame pivotally 10 mounted in the casing below said shaft, a rigid grinding-surface carried by said frame, a flexible device connected to said frame and winding mechanism for said flexible device, the pivot of said frame being located below 15 the grinding-surface when the frame is in operative position.
2. In a machine of the character described, the combination of a casing, revolving hammers or beaters mounted therein, a frame pivotally mounted in said casing, a grinding-surface carried by said pivotally-mounted frame, said frame being adapted to be actuated to dump the material resting on said grinding-surface, a chain connected to the 20 free end of said frame, a winding-shaft around which said chain is wound to restore said frame and grinding-surface to normal position, a hand-wheel on said shaft for rotating same, a ratchet-wheel carried by said shaft, and a coöperating pawl for engaging 25 said wheel to prevent retrograde movement of said shaft; substantially as described.
3. In a machine of the character described the combination of the casing, revolving hammers or beaters arranged therein, a pivotally- 30 mounted frame inside of the casing and provided with a rigid grinding-surface, removable devices projecting laterally from said frame through openings in the side walls of 35 the casing, and wedges coöperating with said devices for adjusting the free end of the frame to take up wear between the grinding-surface and the ends of the hammers. 40

4. In a machine of the character described, the combination with a casing, pivotally-mounted revolving hammers or beaters, a frame pivotally mounted in said casing, a grinding-surface carried by said frame, a flexible device connected to said frame, winding mechanism for said flexible device, 45 and independent means for adjusting the frame when in operating position; substantially as described.

5. In a machine of the character described, the combination of a casing, pivoted revolving hammers or beaters, a pivoted frame mounted in the casing, a grinding-surface carried by said frame, a chain connected to said grinding-surface, a winding mechanism coöperating with said chain, removable projections which are designed to be connected to and disconnected from said frame from the outside of the casing; and means coöperating with said projections for adjusting the free ends of said pivoted frame and its carried grinding-surface when the same is in operating position; substantially as described. 55

6. In a machine of the class described, the combination with a casing, of revolving beaters mounted therein, a pivotally-mounted 70 grinding-surface arranged inside of the casing and provided with members that project laterally through slots in the side walls of the casing, and wedges at each side of the casing coöperating with the laterally-projecting 75 members on the grinding-surface to change its position relatively to the ends of the beaters; substantially as described.

In testimony whereof I hereunto affix my signature, in the presence of two witnesses, 80 this 14th day of July, 1905.

MILTON F. WILLIAMS.
